UNITED STATES PATENT OFFICE.

ROLLAND II. HORNE, OF RYE, NEW YORK, ASSIGNOR TO THE J. L. MOTT IRON WORKS, OF NEW YORK, N. Y.

DESIGN FOR A HEATING-COIL.

SPECIFICATION forming part of Design No. 29,890, dated December 27, 1898.

Application filed December 1, 1898. Serial No. 698,010. Term of patent 7 years.

To all whom it may concern:

Be it known that I, ROLLAND II. HORNE, a citizen of the United States, residing at Rye, in the county of Westchester and State of New York, have invented and produced a new and original Design for a Heating-Coil, of which the following is a specification.

In the accompanying drawings, Figure 1 is an elevation, and Fig. 2 is a plan of the design of the heating-coil.

This heating-coil diminishes in size upwardly and is longer than it is wide.

The leading feature of this design consists in the substantially semicircular ends and

straight sides to the coil of pipe, such coil being largest in measurement at the bottom and tapering upwardly, so that the top is much the smallest, as shown.

I claim—

The design for a heating-coil substantially as herein shown and described.

Signed by me this 25th day of November, 1898.

ROLLAND II. HORNE.
